2,226,093

METHOD OF WEAVING LADDER WEB AND
PACKAGING THE SAMEGeorge E. Colby, East Providence, R. I., assignor
to International Braid Company, a corporation
of Massachusetts

Application August 30, 1939, Serial No. 292,665

3 Claims. (Cl. 139—291)

This invention relates to a ladder web construction where the exterior faces of the two main webs differ in color characteristics, the webs being connected together by cross members, and this invention has for one of its objects an arrangement of the main webs so that the slats carried by the cross members may be satisfactorily closed when the ladder construction is utilized in a Venetian blind.

Another object of the invention is to provide a ladder web construction having webs of different colors, one of which colors is a light color to be placed on the outer side of the Venetian blind and the other web of which is a darker color designed to be placed on the inner surface of the Venetian blind for the harmonizing in different room color schemes, with an arrangement between these two main webs so that they will be substantially equal in length or if any variation occurs this variation will be such as to provide the lighter colored tape longer in length to provide proper closing of the blind by tilting of the slats thereof.

Another object of the invention is to arrange for this proper length characteristic of the main webs by the packaging of the ladder construction in a form so that the lighter colored web will be on the outside of the package or roll and thus will maintain a greater radius for any angle of 30 arc and thus a greater length than its companion web of darker color.

Another object of the invention is to arrange for the proper length characteristic of the main webs both by the tension or take-up of the warps in the main webs and the packaging of the ladder web construction as it is taken from the loom.

With these and other objects in view, the invention consists of certain novel features of construction, as will be more fully described, and particularly pointed out in the appended claims.

In the accompanying drawing:

Fig. 1 is a side elevation of a ladder web construction supporting the cross slats of a Venetian blind;

Fig. 2 illustrates this blind in partially closed position;

Fig. 3 illustrates schematically the weave arrangement of the ladder construction;

Fig. 4 illustrates diagrammatically the travel of the warps in the loom and the rolling of the same; and

Fig. 5 illustrates a package of woven ladder construction.

In the hanging of Venetian blinds where lad-

der web having two main webs of different color characteristics is used, difficulty is often experienced because the workman hanging the blind does not have the option to shift the ladder web from side to side or end to end as where the main webs are both of the same color characteristics as he must for proper hanging place the light colored web on the outside of the blind and the dark colored main web on the inside of the blind for color matching of the room, and if the main webs are not of the same length or the dark web is longer, the blind will not properly close. At the present time it will be noted on the market that it is the custom to package ladder web construction in rolls with the dark colored web, where two colors are used, on the outside. In order to obviate this difficulty, I have arranged to place different tensions on the webs of different colors with the greater tension on the web of light color and to package this ladder construction with the light colored web on the outside and the dark colored web on the inside so that if there be any difference in length, by reason of the packaging, the lighter colored web will be the longer and the blind will properly close, and the following is a more detailed description of the present embodiment of this invention, illustrating the preferred means by which these advantageous results may be accomplished:

With reference to the drawing, I have illustrated an integrally woven ladder construction consisting of a main web 10 of light color and a main web 11 of dark color. The cross members 12 consist of warp threads some of which are of the color of the main web 10 and some of which are of the color of the main web 11. The warp threads 13 corresponding in color to the main web 10 as illustrated in Fig. 3 are woven into this main web and the warp threads 14 which are of the color corresponding to the web 11 are woven into the web 11. The wefts such as 16 are all of one color which may be the color of either of the two webs. This arrangement is more fully disclosed in my co-pending application, Serial No. 266,951, filed April 10, 1939.

In weaving this woven ladder formation the warp threads of the light color in main web 10 will be placed under less tension and therefore have more take-up than the warp threads of the darker color main web 11 and this difference in tension and take-up will be such that for average conditions of atmospheric moisture and other conditions which change dimensions of textiles, a shrinking will occur greater in the dark colored fabric than in the lighter colored fabric after the

same comes from the loom so that the main webs will be of substantially equal length. I have found in practice that if one hundred units of weight are placed upon the warp yarn of the dark colored main web 11 approximately seventy-five units of weight will be placed upon the warp yarns of the lighter colored main web 10. In other words, this would be approximately the proportion which would be right in the average ladder web construction being made in accordance with this invention at the present time. It is to be understood that this amount may be varied, however, in accordance with the requisites above, which I have pointed out.

15 In the diagrammatic showing in Fig. 4 the warp yarns 18 which form the light colored main web 10 are drawn from a warp beam (not shown) about a suitable guide roll 19 while the warp yarns 20 of the main web 11 are drawn about 20 a suitable guide roll 21 from a warp beam 22. These webs as well as the cross tapes are woven in the loom by manipulation of the harnesses 23 and the webs together then pass over the breast-beam 24, sand roll 25, guide roll 26, to be packaged as at 27. The light main web 10 is on the outside as the tape passes over the sand roll 25 where the webs are under tension and any extension may occur. The reeling at 27 is under little or no tension.

30 From this reeling the web is unrolled and clipped to sever certain portions of the ladder members and then when repackaged as shown at 28 the light colored web 10 is on the outside as on the sand roll and the dark colored web 11 is on the inside, all being wound upon 35 a suitable core 29. In this manner any stretching which occurs by reason of the longer path of travel of the outer of the two main webs will occur in the light colored main web and while 40 the web is in this coiled condition readjustment as to shrinkage will not readily occur. However, when the web is hung and thus exposed to moisture shrinkage can occur and will occur to a greater extent in the light colored web which 45 was woven under greater tension and with less

take-up than in the dark colored web and under average conditions a suitable adjustment will be such that these webs will assume substantially the same length. The longer length, however, from the beginning is in the light colored outer 5 web affording at all times proper closing of the slats 29 of the blinds which will cause an inclination of the slats as shown in Fig. 2.

The foregoing description is directed solely 10 towards the construction illustrated, but I desire it to be understood that I reserve the privilege of resorting to all the mechanical changes to which the device is susceptible.

I claim:

1. A rolled package of a band of integrally 15 woven ladder construction comprising a pair of web structures, one of light color and another of a darker color, cross members connecting said webs, said lighter color web having more warp take-up than said darker web and said package 20 having the lighter color web provided on the outer side of the rolled package whereby it is disposed along a greater radius and thus along a greater extent for any angle of arc than the darker-colored web. 25

2. The method of providing a ladder web package of differently colored webs, which consists in weaving two webs of different colors, one light color and one of dark color with ladder members woven to connect said two webs, and 30 in so weaving providing substantially greater warp tension on the warps of the web of dark color than on the corresponding warps of the light color. 35

3. The method of providing a ladder web package of differently colored webs, which consists in weaving two webs of different colors, one light color and one of dark color with ladder members woven to connect said two webs, and in so weaving applying substantially less warp tension 40 on the warps of the web of light color than on the corresponding warps of the dark color, and rolling said woven structure with the light colored web on the outside of said roll. 45
